UNITED STATES PATENT OFFICE

TOBIAS G. JASPER, OF BROOKLYN, NEW YORK

PRESSING MACHINE

Application filed February 6, 1932. Serial No. 591,277.

This invention relates to garment pressing machines, and more particularly to the means for taking up the stress and strains developed in such machines during the various pressing operations.

Owing to the enormous strains developed in pressing machines during the pressing operations, it has been the custom to make the various parts of such machines abnormally heavy and to add heavy castings to brace and rigidly tie the supporting frame of such machines together while in operation. This excessive weight adds considerably to the cost of the machines as well as to the difficulty in the handling during transportation and installation of such machines. Likewise it limits the number of machines that can be safely installed upon a floor and despite the precautions taken, the breakage of pressing machine parts is not eliminated.

The main object of my invention is to overcome the above undesirable features inherent in the present day garment pressing machines.

Another object of my invention is to provide a resilient bed plate that will take up the strains and stresses developed during the pressing operation and at the same time act as a support for various parts of the machine and effectively tie together the balance of the supporting structure of such machine, thus permitting the various parts of the machine to be made substantially light in weight.

Another object is to produce a device of the character described in which the maximum simplicity of construction and operation is secured.

Other objects and advantages will appear as the nature of the improvements is better understood, the invention consisting substantially in the novel arrangement and co-relation of parts herein fully described, and illustrated in the accompanying drawings, wherein similar reference characters are used to describe corresponding parts throughout the several views, and then finally pointed out and specifically defined and indicated in the appended claims.

The disclosure made the basis of exemplifying the present inventive concept suggests

a practical embodiment thereof, but the invention is not to be restricted to the exact details of this disclosure, and the latter, therefore, is to be understood from an illustrative, rather than a restrictive standpoint.

The inventive idea involved is capable of receiving a variety of mechanical expressions, one of which, for the purpose of illustration, is shown in the accompanying drawings, in which—

Figure 1 is a side view of a pressing machine partly in section in which one form of my invention is shown, and

Figure 2 is a top plan view thereof, with parts broken away for the sake of clearness.

Referring now to the drawings in detail, 5 indicates the lower or supporting framework of a pressing machine to the top of which is secured by means of bolts 6, a resilient bed plate of comparatively light weight. A table 70 top 8 usually made of wood overlies the said plate and is suitably secured to the frame.

Secured to the rear of the plate 7 by means of bolts 10 is a bracket 11 provided with ears 12 in which there is suitably journalled a shaft 13 upon which there is pivotally mounted a lever 14 to the lower arm 15 of which there is connected a connecting rod 16 in operative engagement with a depressible foot lever 17 pivoted at 18, said lever being maintained in upper position by a spring 19. The lever 14 is provided at its upper end with an arm 20 terminating in upper and lower bearings 21 and 22 respectively. Between the said bearing there is swingingly supported on a rod 23, a bracket 24 having a slideway 25 in which there is slidably supported a bar 26. The said slidebar terminates at its forward end in a hub 27, through which passes a stud 28 which pivotally supports a pressing iron 29 adapted to be pressed against a pressing buck 30, secured by means of bolts 31 to the plate 7, the base of said buck passing through an opening in the table 8.

By depressing the foot lever 17 against the tension of the spring 19 the lever 14 is rocked about its pivot 13 causing the iron 29 to be brought down against the buck 30. It will be seen from the drawings that due to the connections 14, 24 and 26 a comparatively

large leverage is produced, especially so if the bar 26 is extended so as to bring the iron into pressing position at either of the ends 30a or 30b of the buck. This large leverage 5 greatly multiplies the pressure exerted by the foot lever 17 and the iron 29 exerts an enormous pressure against the buck which in the present day machine transfers the said pressure to the supporting structures as well as 10 to the various other parts of the mechanism connected to the pressing iron. Due to this pressure and the lack of resiliency of the present day pressing machines, one or more parts of said machines becomes impaired after some 15 use, and eventually snap or break during a pressing operation.

In my improved machine, however, this is impossible, as any pressure exerted on the buck will cause the resilient plate 7 to give 20 or spring and cause a breathing or heaving action of the said plate and carry with it the bracket 12 as well as the connections 14, 24 and 26, thus relieving the said parts of any excess strain or pressure.

25 It is to be understood that the table top 8 is not securely fastened down to either the plate 7 or the frame 5, but merely lies on the plate and held against lateral movement only by any suitable means. The said table is only 30 utilized to support garments to be pressed and may entirely be dispensed with if desired. The buck 30 however as previously stated is fastened to the plate 7 which is preferably thin and resilient, consequently when 35 pressure is exerted on the buck at either end 30a or 30b thereof, a great strain is put on the plate which strain is not transferred to the frame or any rigid part connecting the said frame, but is taken up by the resiliency 40 of the plate causing same to warp temporarily and act as a spring bumper.

From the foregoing it will be seen that I have provided means in a pressing machine that will effectively take up any undue 45 stresses and strains from the supporting structure as well as the operating parts of the machine and prevent the said parts from becoming impaired and eventually breaking when the machine is being used.

50 It will further be seen that due to this means the operating parts, as well as the supporting structure, may be made comparatively light in weight thus eliminating the disadvantages and objectionable features of the 55 present day pressing machines.

Having described my invention what I claim as new and desire to secure by Letters Patent is:

1. In a pressing machine, a supporting 60 frame, and a resilient pressing-apparatus-carrying plate connected thereto for the purpose specified.

2. In a pressing machine, a supporting 65 frame, a resilient bed plate connected thereto, a pressing buck, a pivotally mounted le-

ver operatively connected to the said plate, pressure applying means connected to one end of the said lever, and a movable pressing iron carried by the other end of the said lever and adapted to be brought into pressing engagement with the buck.

3. In a pressing machine, a supporting frame, a resilient bed plate connected thereto, and pressing apparatus carried by the said plate and adapted to move therewith when 75 pressure is applied thereto.

4. In a pressing machine, a supporting frame, a resilient bed plate connected thereto, a pressing buck at one end of the said plate, a bracket secured to the said plate at 80 the end opposite to the pressing buck, a lever pivotally supported on the said bracket, a movable pressing iron pivotally carried by the said lever at one end thereof, the said iron being adapted to be brought into pressing contact with the buck, and pressure applying means connected to the other end of the said lever.

In testimony whereof I hereunto affix my signature.

TOBIAS G. JASPER.
